UNITED STATES PATENT OFFICE.

HERMAN G. BEACH AND HARRY W. WILCOX, OF WATERTOWN, NEW YORK.

DESIGN FOR A PUZZLE-BOARD.

SPECIFICATION forming part of Design No. 35,015, dated August 27, 1901.

Application filed July 20, 1901. Serial No. 69,156. Term of patent 7 years.

To all whom it may concern:

Be it known that we, HERMAN G. BEACH and HARRY W. WILCOX, citizens of the United States, residing at Watertown, in the county of Jefferson, State of New York, have invented and produced a certain new and original Design for Puzzle-Boards, of which the following is a specification, reference being had therein to the accompanying drawings.

- 10 Figure 1 is a plan view of a puzzle-board, showing the new design; and Fig. 2 is a cross-section thereof upon the line 2 2.

As shown in the drawings, the leading or material feature of the design consists of the 15 series of circular figures extending in parallel lines at a right angle to each other to form a cross having arms of equal length, said figures being connected together by diamond-shaped figures radiating from a central circular figure, thus producing an arrangement 20 of four rectangular figures at the different sides of a central rectangular figure. The body A is circular in outline and provided at the periphery with an annular wall A', extending at an angle to the body. Upon this 25 body A series of circular figures B and B' are arranged in three parallel rows, two series of said figures extending at a right angle to each other, so as to form a cross having arms of

equal length. The central row B' of circular figures in each series has radiating from one figure thereof a series of diamond-shaped figures C, which terminate at the outer circular figures of each parallel row and the adjacent figures of the central row B'. This arrangement of the circular and diamond shaped figures presents a grouping of four rectangular figures about a central rectangular figure, each of said rectangular figures being composed of the diamond-shaped figures so proportioned as to terminate at the circular figures forming the outline of the rectangular figure. In the illustration given eight diamond-shaped figures are embodied in each element of the main design.

Having described our invention, what we claim as new, and desire to secure by Letters Patent, is—

The design for a puzzle-board as herein shown and described.

In testimony whereof we affix our signatures in presence of two witnesses.

HERMAN G. BEACH.
HARRY W. WILCOX.
